[57] CLAIM

The ornamental design for a shoe sole foot frame, as shown and described.

DESCRIPTION

FIG. 1 is a side elevational view of one side of a shoe sole foot frame showing my new design;

FIG. 2 is a side elevational view of the other side of the shoe sole foot frame shown in FIG. 1;

FIG. 3 is a rear elevational view of the shoe sole foot frame shown in FIG. 1;

FIG. 4 is a cross-sectional view taken generally along line 4—4 of the shoe sole foot frame shown in FIG. 1; and

FIG. 5 is a cross-sectional view taken generally along line 5—5 of the shoe sole foot frame shown in FIG. 2. The broken line showing of a shoe upper and sole in FIGS. 1 and 2 and a shoe sole in FIGS. 3 and 5 is for illustrative purposes only and forms no part of the claimed design.
